(57) **CLAIM**

The ornamental design for a shoe interior, as shown and described.

DESCRIPTION

FIG. 1 is a front perspective view of the shoe interior in accordance with the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom plan view, showing an alternate environment.

The broken lines in the shoe are included for purposes of illustrating environment and form no part of the claimed design.

1 Claim, 4 Drawing Sheets
